UNITED STATES PATENT OFFICE.

FRANK E. BUCHANAN, OF ROCKFORD, ILLINOIS, ASSIGNOR TO NATIONAL LOCK COMPANY, OF ROCKFORD, ILLINOIS, A CORPORATION OF ILLINOIS.

REVERSIBLE CABINET-LATCH.

1,254,882.

Specification of Letters Patent. Patented Jan. 29, 1918.

Application filed October 22, 1915. Serial No. 57,232.

To all whom it may concern:

Be it known that I, FRANK E. BUCHANAN, a citizen of the United States, residing at Rockford, in the county of Winnebago and 5 State of Illinois, have invented certain new and useful Improvements in Reversible Cabinet-Latches, of which the following is a specification.

This invention relates to latches of the 10 character used on kitchen cabinets and like articles of furniture.

The object of the invention is to produce an improved construction which is readily reversible so that it is equally well adapted 15 for use with either right-hand or left-hand opening doors, and a special aim of the invention is to produce a latch of this character which comprises a minimum number of parts and is extremely simple and cheap 20 to manufacture, which is pleasing in appearance and which may be quickly and easily mounted in either one of two reversed positions.

In the accompanying drawings, Figures 25 1 and 2 are perspective views illustrating two forms of latches embodying the features of my invention. Figs. 3 and 4 are plan views of these two forms respectively, parts being shown in section. Fig. 5 is a 30 front elevation of the form shown in Figs. 1 and 3, parts being sectioned on the plane of line 5 of Fig. 3. Fig. 6 is a front elevation of the form of latch shown in Figs. 2 and 4. Figs. 7 and 8 are front elevations 35 of the two forms, respectively, illustrating the latches in a reversed position.

In the drawings, fragments of the door and its casing are indicated respectively by the letters A and B.

40 Referring first to the form shown in Figs. 1, 3, 5 and 7, the latch comprises a bolt 10 having its free end bent to provide a finger-piece 11, the opposite end of said bolt being pivotally supported upon a screw 12 passing therethrough. This screw also passes 45 centrally through a shell 13 which comprises a circular plate having an angular peripheral flange abutting against the face of the door A, said flange having a notch or slot 50 14 therein through which the bolt 10 passes, said notch being of greater length than the width of the bolt to permit the necessary play of the bolt. The shell is rotatably positioned with the lower wall of the notch 55 14 in place to support the latch 10 in a sub-

stantially horizontal position, the shell being fixed in such position by suitable means, such as a brad 15.

In order to prevent binding of the bolt 10 by turning the screw 12 down too tightly 60 thereon a thrust bushing 16 of greater length than the thickness of the bolt is mounted in the hole of the bolt and is adapted to abut at opposite ends against the face of the door A and the inner side 65 of the shell 13.

The bolt 10 is arranged to coöperate with a suitable catch 17 which may comprise a conical head having a reduced shank adapted to be driven into the casing B. When the 70 door A is open, the lower end of the slot 14 of the shell 13 supports the bolt 10 in position so that the bolt will ride up on the inclined head of the catch 17 and drop behind said head when the door is closed. 75

From a comparison of Figs. 5 and 7, it will be seen that when the latch is to be mounted in a reversed position, as in Fig. 7, it is only necessary to rotatably adjust 80 the shell 13 so as to bring the opposite end of the slot 14 into supporting position beneath the bolt 10, the shell being then fixed in such position by the brad 15.

The bolt may be offset, or bent, as at 18, to prevent it from binding against the casing B. 85

In the construction shown in Figs. 2, 4, 6 and 8, the screw 12^a does not pass through the shell 13^a, but the bolt 10^a is first attached to the door A and the shell is afterward attached by suitable means such as brads 19. The bushing 16^a acts, in a manner already described, to prevent the screw from binding the bolt. A cup or boss 20 is formed in the shell to accommodate the 90 head of the screw. The shell 13^a and the boss 20 are elongated or elliptical in shape and the notch 14^a through which the bolt extends is located approximately midway of one of the longer sides of the shell flange. The shell is attached to the door A in such 95 position with respect to the bolt and screw 12^a that the lower end of the notch 14^a will be in supporting position with respect to the bolt when the door is open. As will be understood by a comparison of Figs. 6 and 8, this coöperative relation of the notch and bolt may be readily established in either of the two reversed positions of the latch by 100 vertically adjusting the position of the shell 110

with respect to the location of the bolt and the screw 12^a, the elongated shape of the boss 20 accommodating the head of the screw in either of such positions.

5 The form of catch 21 shown by way of example comprises a base plate and an angular projection 21^a having an inclined front edge and a notch or shoulder to receive the bolt. The offset 18^a of the bolt is 10 sufficient to accommodate the base portion of the catch. 11^a indicates the finger-piece on the bolt 10^a.

15 As will be seen, the latches herein disclosed are equally well adapted for use in either of two reversed positions, as for right or left-hand doors, it being only necessary to adjust the position of the shell with respect to the bolt or its supporting screw, so as to bring one or the other of the opposite 20 ends of the notch in the shell into proper position.

25 The foregoing minute description of the preferred embodiments of my invention is not to be understood as a limitation of the invention to the details disclosed, except as recited in the appended claims.

I claim as my invention:

1. A reversible cabinet latch comprising 30 a bolt, a fastening device on which one end of the bolt is pivotally supported, a shell inclosing said end of the bolt and the fastening device and comprising a plate having an angular peripheral flange, said flange

having an elongated slot through which the bolt projects, and a catch to coöperate with 35 said bolt, the parts being arranged to be mounted in either of two reversed positions, in which the shell is in different relative positions with respect to the pivot of the bolt and the catch to bring one or the other 40 of the opposite ends of said slot into supporting relation to the bolt.

2. A reversible latch comprising a bolt, a pivot for same, a catch to coöperate with the bolt, and a shell inclosing the pivot end 45 of the bolt and provided with a slot through which the bolt projects, the latch being reversible and the shell being shiftable with respect to the pivot to bring either end of 50 said slot into supporting relation to the bolt.

3. A reversible latch comprising a bolt and its pivot, a catch for the bolt, and a shell inclosing the pivoted end of the bolt 55 and having a slot through which the bolt extends, said shell being partially rotatable with respect to said pivot, to bring either end of the slot into supporting relation to the bolt.

In testimony whereof, I hereunto set my 60 hand in the presence of two witnesses.

FRANK E. BUCHANAN.

In the presence of—

A. P. HARD,
E. LUTZHOFF.
